UNITED STATES PATENT OFFICE.

CHARLES THOMAS GIBNEY, OF LAPORTE CITY, IOWA.

OILER.

1,102,333.

Specification of Letters Patent.

Patented July 7, 1914.

Application filed March 1, 1913. Serial No. 751,528.

To all whom it may concern:

Be it known that I, CHARLES THOMAS GIBNEY, a citizen of the United States, residing at Laporte City, in the county of Black Hawk and State of Iowa, have invented certain new and useful Improvements in Oilers, of which the following is a specification, reference being had therein to the accompanying drawing.

10 This invention relates to oiling devices for explosive engines and has for its object the production of an efficient fountain oiler to be used on motors of automobiles where the "splash" system is used, such as for instance, the type of oiler which is now used in connection with standard types of automobiles.

Another object of this invention is the production of a simple and efficient means 20 whereby the height of the oil within the crank cylinder may be regulated so as to keep the oil at a predetermined point at all times.

With these and other objects in view, this 25 invention consists of certain novel constructions, combinations and arrangements of parts, as will be hereinafter fully described and claimed.

In the drawings:—Figure 1 is a top plan 30 view of the lubricating device attached to an engine. Fig. 2 is a central longitudinal section thereof. Fig. 3 is a vertical section through the gage glass. Fig. 4 is a detail perspective of the supply tank partly broken 35 away. Fig. 5 is a detail view of the gage and clamp therefor. Fig. 5^a is a transverse sectional view taken on the line *x*—*x* Fig. 5. Fig. 6 is a longitudinal section of the valve used in connection with the present device. 40 Fig. 7 is a detail perspective of the clamp used for adjusting the feed hose in a set position. Fig. 8 is a view of the blank from which the clamp illustrated in Fig. 7 is formed. Fig. 9 is a perspective view of the 45 part of the blocks which are adapted to clamp the flexible pipe or hose through the gage glass. Fig. 10 is a detail perspective of one of the clamping yokes for attaching the supply tank to the frame of the vehicle.

50 By referring to the drawings, it will be seen that 1 designates the frame of the vehicle which carries an oil supply tank 2 which may be placed at any convenient point upon said frame adjacent the engine. This 55 tank 2 is held in place upon the frame by means of the substantially U-shaped clamp

ing members 3 which have their ends passing through the side members of the frame 1 and held firmly in engagement therewith by means of nuts 4. The tank 2 is provided with a supply opening 5 which supply opening 5 is normally held sealed by means of a sealing plug 6. The tank 2 is also provided with a base discharge spout 7 which tapers longitudinally and is downwardly and forwardly curved and carries at its outer end a valve 8 which valve controls the passage of oil through the spout 7. The valve 8 is provided at its forward or outlet end with a nipple 9 upon which fits the flexible pipe or hose 10. The flexible pipe or hose 10 has its outer end passing down through the gage glass 11 supported adjacent the crank casing of the engine 12. The hose or flexible pipe 10 is held stationary 75 within the glass 11 by means of a cap 13 and is also gripped by means of the clamping sections 14 which clamping sections hold the pipe 10 in a steady position.

A clamping member 15 is provided with 80 a pair of clamping jaws 16 at its lower end, which jaws pass around the gage glass 11 and firmly hold the clamping member 15 in its correct position. The upper end of the clamping member 15 is also provided with 85 a pair of jaws 17 which jaws encircle the gage in an efficient position to grip the flexible pipe or hose 10. A bracing standard 18 is positioned between the laterally extending ends 19 and 20 of the respective 90 jaws 16 and 17 so as to assist in holding the pairs of jaws in their correct spaced relation. Bolts 21 pass through this standard 18 and the ends 19 and 20 for firmly holding the jaws together. By means of the clamping 95 device as illustrated in Figs. 3 and 7, it will be obvious that the hose 10 may be adjusted to any desired position within the glass 11 by sliding the clamping member 15 along the glass 11. It will be further obvious that 100 this mechanism will allow the height of oil within the crank casing to be regulated by means of adjusting the pipe 10 within the glass 11.

The gage glass 11 is provided with the 105 laterally extending tubular portion 22 which fits into the crank casing 23 for feeding the oil to the crank casing. The tank 2 is normally filled with oil and as the oil falls below a predetermined point in the crank casing, 110 or in other words, below the lower end of the pipe 10, the oil from the tank 2 will flow

through the pipe 10 into the gage glass 11 and from the gage glass to the crank casing 23. The tank 2 is made air-tight so as to prevent oil from obtaining access to the interior of the tank, and under ordinary circumstances, where the oil is above the lower end of the pipe 10 so as to prevent the passage of air through the pipe, the oil will discontinue to flow. As soon as the oil has fallen below the lower end of the pipe 10, as previously stated, the air which may pass through or into the pipe 10 and from there to the tank 2 will flow through the pipe 10 thereby allowing the oil to pass through the pipe and into the crank casing of the engine.

As explained above, if it is desired to change the height of oil within the crank casing, the tube or pipe 10 may be adjusted longitudinally of the casing or glass 11.

Having thus described the invention, what is claimed as new, is:

1. In a lubricator, the combination with a crank case, of a gage receptacle in communication therewith, a supply tank, a flexible tube having its inlet end connected to the tank and its outlet end extending into the receptacle, and a clamp slidably connected to the receptacle, and provided with means for adjusting the outlet end of the tube relative to the receptacle.

2. In a lubricator, the combination with a crank case, of a gage receptacle in com-

munication therewith, a supply tank, a tube carried by the tank and discharging into the receptacle, and a clamp embracing the receptacle and provided with means for holding the discharge portion of the tube in an adjusted position relative to the receptacle.

3. In a lubricator, the combination with a crank case, of a gage receptacle in communication therewith, a supply tank, a flexible tube carried by the tank and having its outlet end adjustable in the receptacle, a valve controlling the supply from the tank, and means slidably engaging the receptacle for holding the outlet end of the tube in adjusted position relative to the receptacle.

4. In a lubricator, the combination with a crank case, of a gage receptacle in communication therewith, a supply tank having a valve controlled outlet, a flexible tube having its inlet end connected to the outlet of the tank and its discharge end adjustable in the receptacle, a supporting standard, and a clamp carried by the standard and having arms embracing the receptacle and jaws for engaging the tube to hold the tube in adjusted position relative to the receptacle.

In testimony whereof I hereunto affix my signature in presence of two witnesses.

CHARLES THOMAS GIBNEY.
